(57) **CLAIM**

The ornamental design for a tent, as shown and described.

DESCRIPTION

FIG. 1 is a first perspective view of a tent showing the claimed new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof with the front flap in an open position.

The broken lines are for the purpose of illustrating portions of the article that form no part of the claimed design.

1 Claim, 8 Drawing Sheets
